UNITED STATES PATENT OFFICE.

LUDWIG W. KAEMPF, OF FORT SCOTT, KANSAS.

TROLLEY.

1,375,591.

Specification of Letters Patent. Patented Apr. 19, 1921.

Application filed February 24, 1920. Serial No. 361,034.

To all whom it may concern:

Be it known that I, LUDWIG W. KAEMPF, a citizen of the United States, residing at Fort Scott, in the county of Bourbon and 5 State of Kansas, have invented certain new and useful Improvements in Trolleys, of which the following is a specification.

This invention relates to improvements in trolleys and more particularly to an improved trolley pole head and the primary object of the invention is to provide a trolley pole head so constructed and mounted that the trolley wheel will follow the wire, in rounding curves or when traveling 15 at high speed, without likelihood of the wheel jumping the wire or imposing any such strain thereon as would be liable to break the wire.

Another object of the invention is to so 20 construct and mount the head of the trolley pole that the head will maintain an upright position and run evenly on the wire notwithstanding the swinging motion of the pole in rounding curves.

25 In the accompanying drawings:

Figure 1 is a view in elevation of the device embodying the present invention;

Fig. 2 is a vertical front to rear sectional view therethrough;

30 Fig. 3 is a vertical transverse sectional view.

In the drawings the trolley pole is indicated in general by the numeral 1 and the upper end portion of the pole, indicated by 35 the numeral 2, is flattened as shown in Fig. 2 of the drawings to provide for the application thereto of the trolley pole head which is indicated in general by the numeral 3. The said head comprises a hollow body pref-

40 erably of the segmental form shown in Fig. 1 and including spaced walls 4 and 5 and connecting walls 6 which extend between and may be integral with the lateral edges of the walls 4 and 5. At its upper or minor

45 end the head is provided with a pair of spaced upstanding bracket members 7 rotatably supporting between them the trolley wheel which is indicated by the numeral 8. It will be understood, however, that while

50 the head 3 in the illustrated embodiment of the invention supports a trolley wheel, some other type of contact member might be supported by the head, as for example, a shoe. It will be observed by reference to the draw-

55 ings, that the axis of the wheel 8 extends transversely with relation to the pole and in

a plane between the planes occupied by the walls 4 and 5 of the head 3. In mounting the head upon the pole, the pole is formed in its upper end portion 2 and near its upper extremity with an opening 9 the wall of which is threaded to receive the intermediate portion of a bolt 10, which intermediate portion of the bolt is threaded into the said opening 9. The end portions of the bolt 60 fit pivotally through openings 11 formed in the walls 4 and 5, and washers 12 and nuts 13 are fitted onto the ends of the bolt and thus hold the head pivotally assembled with the bolt so that the head may have oscillatory movement transversely of the pole.

In order that the head may be normally yieldably held in a centered position with relation to the pole, means is provided which will now be described. The numeral 75 14 indicates in general a spring member which constitutes one element of the means referred to and which includes spaced arms 15 connected at their upper ends by an open eye 16 which fits one end of the bolt 10, the 80 member 14 being disposed against the outer face of the wall 5 of the body of the head 3. From the eye 16, the side members 15 extend downwardly between lugs 17 which are provided upon the outer face of the wall 85 5 of the head and prevent pivotal movement of the member 14 about the bolt 10. A lug 17' is also provided upon the wall 5 and engages the upper side of the eye 16 and prevents upward displacement of the spring 90 member. Near their lower ends the spaced portions of arms 15 extend between the wall 5 and an arcuate guide member 18 which is secured at its ends to the said wall 5 and which has its intermediate portion spaced 95 from the said wall. A bolt 19 is threaded at its intermediate portion into an opening 20 formed in the flattened upper portion 2 of the pole 1 and this bolt near its ends projects through arcuate slots 21 formed in the 100 walls 4 and 5 of the head concentric to the pivot bolt 10, nuts 22 and washers 23 being fitted onto the ends of the said bolt 19. The lower end portions of the arms 15 are slightly bowed outwardly in opposite directions as indicated by the numeral 24 and these portions of the arms engage the opposite sides of the adjacent end of the bolt 19 under normal conditions. Thus the member 14, by its resiliency, yieldably holds the 110 head 3 in an upright or centered position with relation to the trolley pole and any

lateral oscillatory movement of the head is yieldably resisted by one or the other of the arms 15 as will be evident by reference to Fig. 1 and the full and dotted line positions 5 illustrated therein.

From the foregoing description of the invention it will be evident that while the head will normally be held in centered position with relation to the pole, nevertheless 10 it may have oscillatory movement transversely of the pole which movement is, however, yieldably resisted by the resilient arms of the member 14. As a consequence when the pole swings to one side or the other in 15 rounding a curve or because of swaying of the car by which it is supported when the car is traveling at high speed, the head 3 will be maintained in upright position and with its wheel 8 in engagement with the 20 trolley wire regardless of the movement of the pole.

Having thus described the invention, what is claimed as new is:

1. In a device of the class described, the 25 combination with a pole or the like, of a head mounted thereon for transverse oscillatory movement, a contact element carried

by the head, and a pair of spring legs for resisting movement of the head in opposite directions. 30

2. In a device of the class described, the combination with a pole or the like, of a head pivotally supported thereon for transverse oscillatory movement, an abutment element carried by the pole, and means carried 35 by the head and coacting with the abutment element to yieldably resist such movement of the head, said means comprising a spring loop fixed to the head at the loop end and having legs disposed on opposite sides of 40 said abutment element.

3. In a device of the class described, the combination with a pole or the like, of a head pivotally mounted thereon for transverse oscillatory movement, a contact element carried by the head, an abutment element carried by the pole, the head having a slot through which the abutment element projects, and a resilient member disposed 45 against the head and having spaced resilient arms for coaction at their free ends with the opposite sides of the abutment element. 50

In testimony whereof I affix my signature.
LUDWIG W. KAEMPF. [L. s.]
